UNITED STATES PATENT OFFICE

PERCY R. DRENNING, OF BALTIMORE, MARYLAND, ASSIGNOR, BY MESNE ASSIGNMENTS, TO T. H. SYMINGTON AND SON, INC., OF BALTIMORE, MARYLAND, A CORPORATION OF MARYLAND

SIDE FRAME AND JOURNAL-BOX MOUNTING

Application filed October 7, 1926. Serial No. 140,183.

The invention relates to side frame construction and journal box mountings for use in connection with or forming parts of a railway car truck, particularly of the freight car type.

The principal object of the invention, generally stated, is to provide cushioning means for the journal boxes used in connection with the side frames of trucks of that variety in which the truck bolster is ordinarily spring supported, the provision of cushioning means for the journal boxes acting to increase the spring capacity for the car so that heavier loads may be carried without the bringing of undue stresses or strains upon any of the parts.

Another object of the invention is to provide spring supporting means for journal boxes in a truck side frame of the arch bar type, the springs in connection with the journal boxes operating in conjunction with the bolster supporting springs but having a different periodicity so as to avoid synchronism of vibration in the bolster supporting springs and journal box springs so that there will be a tendency to eliminate vertical joggle and to reduce any tendency of the car to develop a roll or side sway.

A more specific object of the invention is to provide journal box cushioning means in which guide means is provided for the cushioning or spring members to insure maintaining them in proper position and against accidental displacement at any and all times.

Another object of the invention is the provision of spring means employed in conjunction with side frames of the pedestal or other type using separable journal boxes, the spring means being adapted to be confined between the journal boxes and adjacent portions of the side frames and being, in some instances, capable of being enclosed within the side frame and consequently protected against damage and against the deteriorating effects of the weather.

A still further object is to provide cushion or absorption means in conjunction with the journal boxes formed as a bank or group of plate springs which not only provide resilience but which act also to develop a certain

amount of friction, the combination of the resilience and the friction acting to absorb sudden shocks and jars in addition to steady ing the action and increasing spring capacity.

A still further object of the invention is to provide a structure of this character in which the journal boxes are mounted for vertical sliding movement with respect to the side frame, spring means being provided for opposing the sliding movement in one direction, and guide means being provided for preventing the journal boxes from moving in any direction other than vertically.

An additional object of the invention is to provide a structure of this character which will be comparatively simple and inexpensive to manufacture, easy to install, positive in action, efficient and durable in service, and a general improvement in the art.

With the above and other objects and advantages in view, the invention preferably consists in the arrangement and combination of parts and detailed structural features to be hereinafter more fully described and claimed, and illustrated in the accompanying drawings in which:

Figure 1 is a side elevation of a portion of a truck frame and journal box mounted therein in accordance with one form of the present invention,

Figure 2 is a fragmentary elevation showing a slight modification,

Figure 3 is a view showing a modified form of spring,

Figure 4 is a side elevation of a portion of a bolster equipped with journal boxes of the pedestal type, the invention being shown applied,

Figure 5 is a detail horizontal cross section taken on the line 5—5 of Figure 4,

Figure 6 is a vertical sectional view showing a different spring retaining means,

Figure 7 is a side elevation of one half of a side frame showing a different spring mounting for the journal boxes,

Figure 8 is a cross sectional view taken on the line 8—8 of Figure 7, the journal box itself being shown in elevation, and

Figure 9 is an end view of the side frame.

Referring more particularly to the draw-

ings, and especially Figures 1 to 3 inclusive, the numeral 1 designates a side frame forming part of a truck of that type in which spring means 2 is provided for supporting the bolster 3. Both ends of the side frame are of course the same and for this reason only one is illustrated as it is entirely sufficient to give a thorough understanding of the invention. Each side of the side frame or each end is formed with an extending portion 4 beneath which is mounted the journal box 5. This box may be of any ordinary or preferred type in most respects though it is of special construction in other respects for cooperation with guide means to be described.

The guide means for each journal box may conveniently comprise an arm or tie bar 6 riveted or otherwise suitably secured at 7 to a bracket or foot piece 8 on the side frame, this arm 6 being apertured for the passage of a plurality of bolts 9 which are arranged in vertical position and which extend through suitable holes 10 in the extension 4. The arm or tie bar 6 is horizontal and may be resilient. In the present instance the bolts 9 are represented as having heads 11 at their lower ends and their threaded upper ends carrying nuts 12 which may be of the castellated type for cooperation with cotters or the like provided for preventing relative movement and separation. The journal box is vertically slidably mounted with respect to these bolts 9 and is provided at its opposite sides with lugs or ribs 13 which cooperate with the guide bolts. Clearly the journal box may move vertically but it will be equally apparent that it cannot move in any other direction.

The cushioning or absorption means operating in conjunction with the journal boxes is here shown as comprising a bank or group of elongated plate springs 14 interposed between the top of each journal box and the underside of the corresponding extension 4, the springs being represented as having their concave sides uppermost with the center of the lowermost plate engaging upon the journal box and the ends of the uppermost plate engaging against the underside of the extension 4. Obviously, means must be provided for preventing dislocation of the cushioning means and for this reason the ends of the plate springs are shown as formed with notches 15 for the accommodation of the bolts, these notches opening out to the ends of the plate springs. The arm 6 above referred to is really a journal box tie and the flexibility thereof is utilized in combinations with the bank of springs.

In addition to the above structure, I may provide a single plate spring 17 beneath the arm or tie bar 6 and arranged with its convex upper side engaging against the underside of the arm or tie bar, the ends being formed with notches for the accommodation of the bolts 9, as illustrated in Figure 2, this plate spring 17

acting simply as a bolt tensioning spring. Obviously, the springs 14 and 17 may be provided with holes 18, as in Figure 3, instead of notches, if desired.

In Figures 4, 5 and 6 I have illustrated the invention as applied to a side frame of the pedestal type, the side frame 19 having an opening 20 therein within which is vertically slidably mounted a journal box 21, the journal box having laterally extending flanges or webs 22 overlying the opposite faces of the side frame for limiting its movement to the vertical. In applying the invention to this type of journal box and mounting, use is made of a group or bank of elongated or plate springs 23 located between the journal box and the top wall of the opening 20, the preferred arrangement being that the springs be disposed with their concave sides uppermost, the ends of the topmost bearing against the top wall of the opening 20 and the center of the lowermost bearing upon the top of the journal box. Clearly, it is necessary to provide means for retaining the springs in place and this means may conveniently consist of vertical ribs 24 formed on the confronting sides of the opening 20 and engaging within notches 25 in the ends of the springs.

Instead of this retaining means, or in addition thereto, the journal box may be formed at its top with spaced upstanding lugs 26 located at opposite sides of the bank or group of springs, as clearly indicated in Figure 6. The springs in any instance may be of any desired shape as for instance they may be rectangular as indicated in Figures 1 and 6 or I may make use of those of a hexagonal shape as indicated in Figure 5, in which event the upstanding guide lugs 26 on the journal boxes would be omitted, the guide means for the springs consisting then only of the ribs 24 engaging within the notches in the springs. The advantage in using springs of the shape shown in Figure 5 is simply the increase in the area thereof as compared with the area of the elongated rectangular type. It might also be mentioned that if the upstanding guide lugs 26 are used as spring retaining means the ribs 24 and notches 25 may be omitted as either means is sufficient unto itself.

In Figures 7, 8 and 9 I have disclosed yet another modification in which the side frame 28 has its end extension 29 formed with a pocket 30 opening out to the end of the extension. The side frame is formed with an opening 31 within which is vertically slidably mounted the journal box 32 which is provided with laterally extending webs, flanges or the like 33 engaging against the opposite faces of the side frame for guiding purposes. The pocket 30 communicates with the opening 31 and is of greater length than the width of the opening to provide ledges 34

for a purpose to be described. The top wall of the pocket is provided near its ends with ledges 35 which are preferably inclined and which are located at points considerably lower than the center of the top wall of the pocket as clearly indicated in Figure 7.

The cushioning or absorption means in this instance comprises a group or bank of elongated plate springs 36 fitting within the pocket 30 and between the ledges 35 and the journal box, the ends of the uppermost plate in the bank engaging these ledges, and the center of the lowermost plate engaging upon a convex bearing member 37 which may be formed integrally upon the top of the journal box or which may be constructed as a separate piece secured thereon, this detail being immaterial.

In the assembling of the parts, it is apparent that the group or bank of springs 36 is introduced through the open end of the pocket, subsequently to which the opening is intended to be closed as by means of an angular closure member 38 fitted into the open end and secured as by bolts 39. The ledges 34 above mentioned serve as means for supporting the springs within the pocket in case the journal box is withdrawn entirely from engagement with the side frame, it being manifestly impossible for the springs to drop out. The purpose of the convex bearing member 37 is to cause flexure of the springs upwardly under load conditions.

In the operation of all forms of the invention, it will be readily apparent that under load conditions the plate springs will be flexed to assist the bolster supporting springs. In the form of the invention disclosed in Figures 1 and 4 the bringing of a load upon the springs operates to flatten them from their normal curved shape whereas in the form disclosed in Figure 7 the weight acts to flex the springs out of their initial flat condition. The effect is the same in either instance inasmuch as movement of the journal boxes is resiliently opposed. As these springs are auxiliary to the bolster supporting springs it is clear that the spring capacity of the car equipped with the invention will be materially increased so that greater loads may be carried without danger of bringing undue strain upon any of the parts. The plate springs operating in conjunction with or in addition to the bolster supporting spring will have the additional effect of preventing jiggling and eliminating car roll or side sway in view of the fact that synchronism is avoided as the periodicity of the two types of springs is entirely different. In every form of the invention it is evident that a larger or smaller number of plate springs may be used depending upon circumstances or other conditions which may develop in the actual carrying out of the invention. Ample means has been provided for guiding the

journal boxes during their movement and for retaining the springs in their proper operative relation to the other parts so that displacement will be positively prevented. The construction, operation and advantages should be readily apparent to one skilled in the art without further explanation.

While I have shown and described preferred embodiments of the invention, it should be understood that the disclosure is merely illustrative of the general principles involved and certain possibilities in the matter of design and arrangement. It should of course be understood that the right is reserved to make all such changes, variations or modifications as will widen the field of utility provided such constitute no departure from the spirit of the invention or the scope of the claims hereunto appended.

Having thus described the invention, I claim:

1. In combination with a truck side frame of the arch bar type, plate spring cushioned journal boxes carried by the side frame.

2. In a railway car truck having a side frame and a spring supported bolster mounted within a window opening in the side frame, journal boxes, and plate spring means located above and cushioning the journal boxes.

3. In a railway car truck having a side frame and a spring supported bolster mounted within a window opening in the side frame, journal boxes, plate spring means located above and cushioning the journal boxes, and retaining means for said spring means.

4. In a railway car truck having a side frame formed with a window opening for the reception of a spring supported bolster, a journal box vertically movably mounted at each end of the side frame, means for guiding the journal box during its vertical movement and preventing movement thereof in any other direction, and a bank of plate springs located between the top of the journal box and the adjacent portion of the side frame, said springs operating in conjunction with the bolster supporting springs for increasing the spring capacity.

5. In a railway car truck having a side frame formed with a window opening for the reception of a spring supported bolster, a journal box vertically movably mounted at each end of the side frame, means for guiding the journal box during its vertical movement and preventing movement thereof in any other direction, and a bank of plate springs located between the top of the journal box and the adjacent portion of the side frame, said springs operating in conjunction with the bolster supporting springs for increasing the spring capacity and having a periodicity of vibration different from that of the bolster supporting springs to break up synchronism of the latter.

6. In combination with a truck side frame of the type having a window opening for the reception of a truck bolster and spring supporting means therefor, journal boxes vertically slidably mounted at the ends of the side frame, and plate spring means supporting the side frame upon the journal boxes, said second named spring means acting in conjunction with the first named spring means and having a periodicity different therefrom to break up synchronism and eliminate car roll.

7. A railway car truck side frame provided at its ends with guide means and abutment means, a journal box vertically slidably mounted along the guide means at each end, a bank of plate springs arranged in engagement with each journal box and the adjacent abutment means, and means for retaining the plate springs against displacement.

8. A truck side frame provided at each end with an opening and a pocket communicating therewith, a journal box vertically slidably mounted within the opening, and a plurality of plate springs arranged in superposed relation within the pocket and engaged by the journal box.

9. A truck side frame provided at each end with an opening and a pocket communicating therewith, a journal box vertically slidably mounted within the opening, a plurality of plate springs arranged in superposed relation within the pocket and engaged by the journal box, the pocket opening out to the end of the side frame, and means for closing said open end of the pocket.

10. A truck side frame provided at each end with an opening and a pocket communicating therewith, a journal box vertically slidably mounted within the opening, and a plurality of plate springs arranged in superposed relation within the pocket and engaged by the journal box, the pocket having a length greater than the width of the opening to define retaining ledges acting to prevent dropping down of the plate springs beyond a certain point upon removal of the journal box.

11. A truck side frame provided at each end with an opening and a pocket communicating therewith, a journal box vertically slidably mounted within the opening, a plurality of plate springs arranged in superposed relation within the pocket and engaged by the journal box, the pocket being formed at its ends with ledges located below the top of the pocket for engagement by the ends of the topmost plate spring of the bank, and the journal box having a convex upper surface bearing against the center of the underside of the lowermost plate spring.

12. A side frame provided at each end with a downwardly opening jaw portion and formed with a pocket above the jaw portion,

a journal box vertically slidably mounted within the jaw portion, and a bank of plate springs located within the pocket in engagement with the top of the journal box and removable from the end of the pocket.

13. A truck side frame provided at each end with an opening and a pocket thereabove, a journal box vertically slidably mounted within the opening, a bank of plate springs located within the pocket and engaged by the journal box, and means for limiting downward movement of the springs to prevent dropping out upon removal of the journal box.

14. A truck side frame provided at each end with an opening, a journal box slidably mounted within the opening, a bank of plate springs located within the side frame and engaging upon the top of the journal box, and means independent of the journal box for limiting downward movement of the springs.

15. A truck side frame provided at each end with an opening and a pocket communicating therewith, a journal box vertically slidably mounted within the opening, a bank of plate springs within the pocket engaged by the journal box, abutment shoulders at the top of the pocket engaged by the springs, movement limiting ledges at the bottom of the pocket for preventing dropping down of the springs, the bolster having a second opening leading into the pocket permitting introduction or removal of the springs.

In testimony whereof I affix my signature.

PERCY R. DRENNING.
